UNITED STATES PATENT OFFICE.

MATTHIAS BROCK, OF BOSTON, MASSACHUSETTS, ASSIGNOR TO THE CONSOLIDATED & MCKAY LASTING MACHINE COMPANY, OF PORTLAND, MAINE.

LASTING-MACHINE.

SPECIFICATION forming part of Letters Patent No. 601,934, dated April 5, 1898.

Application filed April 14, 1896. Serial No. 587,488. (No model.)

To all whom it may concern:

Be it known that I, MATTHIAS BROCK, of Boston, county of Suffolk, State of Massachusetts, have invented an Improvement in 5 Lasting-Machines, of which the following description, in connection with the accompanying drawings, is a specification, like letters and figures on the drawings representing like parts.

10 In United States Letters Patent No. 548,862, granted to me under date of October 29, 1895, I have shown and described a lasting-machine wherein the wipers are made to open and close to wipe the upper over and upon the inner 15 sole and are also connected with a cross-bar which is manually movable to vary the lateral position or adjustment of the wipers to adapt the same to last ends of different inclinations or swing—such, for instance, as lasts either 20 rights or lefts.

15 In this my present invention I have provided one form of means whereby the wipers or lasting devices and the last are automatically and relatively adjustable to adapt said 25 lasting devices or wipers to last ends having different inclinations—that is, a difference in swing—whether the lasts be rights or lefts.

20 My invention further comprehends means automatically and means manually for effecting the relative adjustment of the said end wipers and last to meet the varying swing of 30 a last, whether a right or a left, the said automatic or the said manual means to be employed by and at the will of the operator, according as automatic or manual means is desired.

25 Figure 1, in side elevation, represents the head of a lasting-machine embodying my invention with the toe portion of a boot or shoe 40 to be lasted shown in operative position. Fig. 2 is a front elevation of the apparatus shown in Fig. 1 with the boot or shoe omitted. Fig. 3 is a top or plan view of the apparatus shown in Figs. 1 and 2, showing also a boot or shoe 45 in position to be lasted. Fig. 4 is a longitudinal sectional view of the operative parts of the head, taken on the line $x-x$, Fig. 3; and Fig. 5 is an under side view of the cap for the tipping plate, with the side-wiper plates,

their carriers, and the longitudinally-movable 50 slide-bar upon which they are mounted.

Referring to the drawings, Figs. 1 to 4, inclusive, I have herein shown a tipping-plate holder A, having upturned ends a' to form bearings for journals b b' , respectively, of a 55 tipping plate B, whereby the latter is adapted to rock or tip laterally, suitable springs S (see Figs. 1 and 2) preventing undue movement of the tipping plate upon its journals.

The tipping-plate holder A is mounted on 60 trunnions a^x , extended through longitudinal slots c in the upturned part of the base C, pivoted at C', Fig. 1, to a carriage D, which is adapted to slide longitudinally on the frame, said base C being freely rotatable about its 65 said pivot C' to enable said base and the parts carried thereby to freely adapt themselves to the inclination of the end of the last, as will be hereinafter described.

The rear end of the carriage (see Figs. 1 and 70 3) is herein shown as provided with a rack-bar d to be engaged at times by a suitably-shaped tooth d' on a lever d^2 , pivoted to an ear a^2 on the tipping-plate holder, whereby the head of the machine may, when desired, 75 be manually swung laterally about the pivot C' and, if necessary, held in adjusted position on the carriage. The pivotal point of the head is shown in alinement with the center of the end of the last, and by the lateral 80 adjustment of the head the side-wiper plates or wipers (to be described) are adjusted to the varying inclinations of the sides of the last—for example, the last in a "right" or a "left" 85 boot or shoe.

The base C is shown provided with a rearwardly-extended and upturned horn C², Fig. 1, slotted at C³ to receive a stud a^3 on the tipping-plate holder, and by means of an adjusting-screw a^4 , connected by a ball-and-socket, 90 joint to one end of the horn and extended through a threaded opening in the ear a^2 , the tipping-plate holder A may be tipped upon its trunnions a^x to vary the inclination of the tipping plate from front to rear.

95 A toe-rest e of any suitable construction is herein shown as mounted upon a slide-bar e' , Fig. 2, longitudinally movable in a guide-

way D', forming a part of the carriage and vertically adjustable by means of a cam D² on a cam-lever D³, adapted to rock on a suitable stud by means of a hand-lever D⁴, all as in my other application hereinbefore referred to.

The tipping plate B has a raised portion b² thereon to form a support for an actuating-cam F, provided on its under side or face 10 with a cam-groove f and in its upper face with two cam-grooves f'f², (see Figs. 3 and 4,) for a purpose to be described, the said cam being mounted on a suitable stud F', as clearly shown in Fig. 4.

15 The tipping plate has adjustably connected thereto a bracket g, in which is mounted an elbow-lever g', pivotally connected at g² to a toe-wiper holder g³, the other end of the lever being connected by a knuckle-joint g⁴ to a 20 slide-plate g⁵, adapted to slide in a recess in the tipping plate B and provided with a suitable roller or other stud g⁶ to enter the cam-groove f on the actuating-cam.

The toe-wiper holder is vertically socketed 25 to receive therein the shank g⁷, Fig. 4, of an end-wiper or clasp carrier, shown as a grooved plate g⁸, upon the inner or concaved face of which is secured a pad of leather or other suitable material, which constitutes one form 30 of wiper or clasp to wipe the upper about the end of the last as the said wiper or clasp is elevated by the rocking motion of the elbow-lever g', the latter being actuated by a partial rotation of the cam F.

35 The end wiper or clasp may be free to swing laterally upon its shank g⁷ to accommodate itself to a right or a left boot or shoe, its shank g⁷ being shown as circumferentially grooved, as at g¹⁰, to receive a pin g¹¹, held in the socket, 40 and which restrains said shank against end-wise movement without interfering with the rotation thereof, said shank and its socket being, however, provided with holes g¹², into or through which said pin may be inserted to 45 restrain said shank and its wiper against rotative movement, and thereby lock the same rigidly to the base and parts carried thereby for automatic adjustment, as will be herein-after described.

50 An abutment h, to position the toe of the boot or shoe when placed upon toe-rest e, forms a part of an abutment-plate h', adapted to slide longitudinally in a wiper-carrier support k, shown as a slide-bar movable longitudinally in the cap G, secured to the tipping plate above the actuating-cam by suitable bolts or screws, as 10, Fig. 3. A roller or other stud h² on the under side of the abutment-plate enters the cam-groove f' to 55 be reciprocated thereby, the shape of the cam-grooves f and f' being such that the abutment h is withdrawn from the toe of the boot or shoe as the toe-wiper g⁹ is elevated.

The cap G is recessed upon its under side, 60 as stated, to form a guide for the slide-bar k, having a roller or other stud k' to enter the cam-groove f² and longitudinally slotted at

h² to receive a lug h³ on the abutment, for a purpose to be described.

In the construction herein shown, referring 70 to Figs. 4 and 5, wiper-carriers m are pivoted at m² to the under side of the slide-bar k, which herein constitutes one form of wiper-actuator, said carrier being rocked or swung laterally by means of cam-plates n, secured 75 to the wiper-carriers in suitable manner, as by a screw-and-dowel connection at n², Fig. 5, the cam-plates extending at opposite sides of and above the slide-bar k and having therein slots n' to be entered by fixed pins or studs 80 25 on the under side of the cap G, whereby as the slide-bar k is moved forward the wiper-carriers m will be moved forward and also swung toward each other and about their common center m².

85 Wipers or wiper-plates o are herein shown as mounted at the under sides of the carriers m on the common center m², the said wiper-plates being slotted at o' concentrically to the said center to receive therein suitable adjusting-screws o² on the carriers, whereby the plates may be adjusted upon their carriers independently one of the other to adapt them to the particular shape of the boot or shoe which is to be lasted.

90 The inclination of the sides of the boot or shoe at or adjacent the toe or heel—i. e., the swing—varies according to whether the shoe is a right or a left shoe and also according to the particular style of last, and to 100 adapt the apparatus herein described to act upon either a right or a left boot or shoe or on rights or lefts of different styles it is necessary to laterally adjust the wiper-carriers and the said wipers or wiper-plates and the 105 last relatively preferably about the center of movement m², which latter is located in a line drawn along the bottom of the last from the center of the toe to the center of the heel thereof, and in this instance of my invention 110 such adjustment is provided for by swinging the entire head of the machine about the pivot C' of the base C. By means of this lateral adjustment of the wiper-plates I am 115 enabled to cause the latter to approach the sides of the last uniformly throughout their 120 lengths and to wipe the upper over the last equally, inasmuch as the leading edges of the side-wiper plates can be brought up to the upper to act upon it simultaneously at each 125 side of the toe.

130 It is obvious that the mechanism shown and described, without substantial change and without invention, may be employed at the heel end of a last to last the material thereat and likewise be adjustable thereat to meet differences in swing, for with rights and lefts the heel end of the last varies proportionally as the toe end, and since substantially the same mechanism hereinbefore described is all that would be necessary to accomplish the lasting and adjustment at the heel I have not shown the same.

As in my other application hereinbefore

referred to I have provided a tack or nail puller claw r to engage a tack or nail 50, (see Fig. 3,) driven into the upper at the under side of the center of the toe, said claw being formed on the end of a rocker-arm r' , pivoted at r^2 on the cap G, said arm being rocked on its pivot by means of a dog r^3 , engaged by the lug h^3 on the abutment-plate h' when the latter is moved rearwardly to withdraw the abutment, a pin r^3 on the dog engaging a suitable ear r^4 on the arm r' .

To hold the tack or nail puller in raised position when withdrawn, as described, I have provided a spring-catch s on the cap to engage the foot r^5 of the arm r' .

To prevent the innersole from being moved rearwardly by the wiper-plates when wiping the upper thereover, I have provided a downhold t , adjustably mounted in a hub t' on a rocking arm t^2 , pivoted at r^2 and acted upon by a spring s' to normally lift it, the arm having on its under side a locking-ear t^3 to engage a shoulder 75 on the cap G and retain the downhold in place against the action of the spring. The arm t^2 is slotted at its pivotal point at t^4 to permit longitudinal movement thereof when a lug t^4 on the arm t^2 is engaged by the cam-plates n in their forward movement to thus withdraw the projection t^8 from the shoulder 75, the action of the spring s' then lifting the downhold into inoperative position. A rest t^5 on the cap is located in the path of movement of and acts as a limiting-stop for the upturned end t^6 of the arm t^2 when moved into inoperative position by the spring.

The actuating-cam F is partially rotated in one or the other direction by means of a suitable handle F^2 , movement thereof in the direction of the arrow 100, Fig. 3, acting by or through the several cam-grooves $f f' f^2$ and the intermediate connections to withdraw the abutment h and move the toe-wiper or clasp g^8 to wipe the toe of the upper about the last and also to actuate the tack or nail holder, while the wiper-plates or wipers are moved forward and closed to wipe the upper uniformly and with an equal draft over the sides of the toe of the last. Movement of the handle F^2 opposite to the arrow 100 restores the abutment and wiper plates to their original position ready to last another shoe, the operator moving the tack or nail puller and the downhold into their position by hand.

55 While the base and supported parts of the head may be manually adjusted laterally on the carriage prior to lasting or even after the partial rotation of the cam, in either of which cases the end clasp g^8 is preferably left free to swivel in its socket to adapt itself to the toe when it meets the latter in rising, yet for the most expeditious operation of the machine the pin g^{11} will be inserted in the holes g^{12} to lock the clasp g^8 rigidly to the base and parts carried thereby, including the side wipers, and the handle-lever d^2 is permitted to remain in its elevated position out of engage-

ment with the rack-teeth d' , the fulcrum-screw for the said lever being always screwed up sufficiently to hold the said handle-lever 70 by friction in elevated position, in which case the head will automatically adjust itself to the inclination of the end of the last.

The automatic operation of the machine here shown, briefly stated, is as follows, viz: 75 If the head of the machine has previously been swung up into position to operate upon a left last, as soon as it is raised toward a right last the clasp g^8 on meeting the last will automatically adapt itself to the different inclination of the sides or swing of this right last and will thereby automatically swing the head to which it is rigidly attached by the pin g^{11} into corresponding position, also in proper alinement with this right last, there- 80 by swinging the wipers into proper position with relation to the sides of the last and accomplishing automatically what would otherwise be accomplished through the medium of the handle-lever d^2 , the clasp when pressed 90 tightly against the end of the last furnishing sufficient power to swing the necessary parts automatically into proper position in alinement with the median line of the last.

When the machine is set to operate auto- 95 matically, the end clasp g^8 fulfils the function of and forms one form of positioning device for automatically positioning the parts in proper operative position relatively to and determined by the last.

100 My machine, therefore, is capable of either automatic or manual operation at the will of the operator, and it is evident that my invention is not to be restricted to the particular construction herein shown and described.

105 In another application, Serial No. 637,850, filed May 24, 1897, I have shown different means for obtaining the automatic relative adjustment of the lasting devices and last, and in said other application, Serial No. 110 637,850, I have claimed such automatic relative adjustment broadly and generically.

115 In another application, filed May 24, 1897, Serial No. 637,850, I have shown other mechanisms for accomplishing automatically the right and left adjustment herein referred to to meet the variations in swing presented by the ends of lasts, whether rights or lefts, said other application containing generic claims to mechanism having this capacity for automatic right and left adjustment.

I claim—

1. In a machine for lasting boots and shoes, a head mounted to swing laterally about a relatively-fixed center, a longitudinally-mov- 125 able slide-bar supported in the head, and wiper-plates mounted to swing about a common center on said slide-bar, combined with actuating means to move the wiper-plates forward and to close them over the toe of the last, substantially as described.

2. In a machine for lasting boots and shoes, a laterally-movable head mounted to be swung about a relatively-fixed center, a slide-

bar in the head, wiper-plates, and carriers therefor, mounted to swing about a common center on the slide-bar, and independent adjustable connections between said carriers and wiper-plates, combined with actuating means to move the carriers forward and to close the wiper-plates, lateral movement of the head about its center adjusting the wiper-plates to act uniformly upon the sides of the last, substantially as described.

3. In a machine for lasting boots and shoes, a base mounted to swing laterally about a relatively-fixed center, a tipping-plate holder supported thereby, and a tipping plate carried by the holder, combined with a slide-bar, wiper-plates mounted thereon to swing about a common center, actuating means to move said plates forward and to close them over the bottom of the last, and an adjusting device for the base, to regulate the lateral movement thereof about its pivot, substantially as described.

4. In a machine for lasting boots and shoes, a sliding carriage, a head mounted thereon to swing laterally about a pivot beneath the center of the end of the last, and means to retain said head in lateral adjustment on the carriage, combined with wiper-plates carried by the head, and actuating means to move the said wiper-plates forward and to close them over the toe of the last, substantially as described.

5. In a machine for lasting boots and shoes, a head mounted to swing laterally about a relatively-fixed center, the wipers mounted upon the said head, means on said head to actuate the said wipers to wipe the material over and upon the last or the inner sole thereupon, and means to swing said head laterally to adapt the said wipers to lasts, either rights or lefts, having different inclinations, substantially as described.

6. In a lasting-machine, the combination with lasting devices having a capacity for automatically shifting into one or another position to meet ends of right or left shoes presenting differences of swing, of means for manually shifting said lasting devices also into position for meeting ends of right or left shoes presenting differences of swing, substantially as described.

7. In a lasting-machine, the combination

of toe-lasting devices and a last-supporting jack, capable of a relative movement about a center substantially in vertical alinement with the central point of the toe of a last on the jack, mechanism for relatively laterally moving the toe-lasting devices and jack to change the longitudinal inclination of the toe-lasting devices and jack to adjust the toe-lasting devices for right and left shoes.

8. In a lasting-machine, the combination with lasting devices to last the end of a shoe and means independent of the last to actuate said lasting devices of a swinging support for said lasting devices said swinging support enabling said lasting devices to be adjusted to meet the varying swings of last ends whether rights or lefts.

9. In a lasting-machine, the combination with lasting devices to last the end of a shoe of a swinging support for said lasting devices said support being mounted to swing about a center substantially under the center of the adjacent end of the last, to enable said lasting devices to be adjusted to meet the ends of lasts whether rights or lefts presenting a difference of swing.

10. In a lasting-machine, the combination with lasting devices to last the end of a shoe of a swinging support for said lasting devices, means independent of a last to actuate said lasting devices, and means automatically to swing said support with its said lasting devices to adapt the latter to act upon last ends whether rights or lefts presenting a difference of swing.

11. In a lasting-machine, the combination with lasting devices to last the end of a shoe of a swinging support for said lasting devices means independent of the last to actuate said lasting devices means automatically to swing said support with its said lasting devices to adapt the latter to act upon last ends whether rights or lefts presenting a difference of swing and locking means to lock said swinging support in position.

In testimony whereof I have signed my name to this specification in the presence of two subscribing witnesses.

MATTHIAS BROCK.
